TELEVISION ANTENNA

Julius Tunkl, Chicago, Ill.

Application June 10, 1954, Serial No. 30,896

Term of patent 14 years

(Cl. D26—14)

To all whom it may concern:

Be it known that I, Julius Tunkl, have invented a new, original, and ornamental Design for a Television Antenna, of which the following is a specification, reference being had to the accompanying drawing, forming a part hereof.

Fig. 1 is a front elevational view of the television antenna embodying the design of the present invention;

Fig. 2 is a sectional view taken on line 2—2 of Fig. 1; and

Fig. 3 is a top plan view of Fig. 1.

I claim:

The ornamental design for a television antenna, substantially as shown.
